ADJUSTABLE SASH AND FRAME

Joseph E. Haynes, Baltimore, Md.

Application August 15, 1951, Serial No. 241,983

4 Claims. (Cl. 20—52.2)

1

This invention relates to window construction for buildings and walls, where such are commonly employed, and more particularly to a frame and sash structure of the type that has removable features, draft prevention qualities, and makes the use of sash weights unnecessary.

In a particular form of frame and sash structure, frictional holding devices are mounted on the peripheral surfaces of the sash to guide and frictionally hold the sash in the channels of the window frame, as well as to provide features of removability. Such a form is indicated in the application, Serial No. 196,996, filed by the applicant on November 22, 1950 for Letters Patent of the United States. There are certain limitations to this form, which the present application is designed to overcome. In the first place, the holding devices consist of rollers of irregular contour traveling on rails in the window frame in such a manner as to provide a wedging effect that will bring the sash structure tightly against themselves and the ribs forming the channels, in which the sash slides. The specific structural details of the holding device used in this invention provide for rolling contact that will hold securely when the sash is positioned to suit the user, while at the same time permitting the sash to be readily operated by the user. Further the device is automatic in action and easily controlled by the operator. It is simple in construction, attractive in appearance and can be produced at relatively low cost.

One object of this invention is to provide a new and improved holding device and window construction that will avoid one or more of the disadvantages and limitations of the prior art.

Another object of the invention is to provide a window structure including an arrangement that will permit its manipulation to prevent undue air and rain leakage between the sashes and window frame; be removable and replaceable readily; and having a holding device incorporated in it to avoid the need for sash weights.

A further object of the invention is to provide a new and improved window sash construction that will tend to bind itself against leakage in the frame and otherwise anticipate any tendency to rattle or free itself from the holding device used with it.

Other objects of the invention will become apparent as the invention is more fully set forth.

To illustrate the general principles of the invention, operation and its conformity with the above objects, reference is made to the accompanying drawings. These drawings in conjunc-

2

tion with the following explanation present a particular form by way of example that will enable the invention to be fully appreciated while the claims emphasize the scope of the invention.

5 In the drawings:

Figure 1 is a general view of a window frame and sashes embodying this invention;

Figure 2 is a sectional view taken on line 2—2 of Figure 1;

10 Figure 3 is a sectional view taken on line 3—3 of Figure 1;

Figure 4 is a sectional detail of the leakproof joint used between the upper and lower sash;

15 Figure 5 is a diagrammatic sectional view showing how the sashes are tilted out of the frame for removal or replacement;

Figure 6 shows a sectional part of the sash upright showing the contours of the face designed to cooperate with the inside of the window frame at the side where the holding unit is not employed;

20 Figure 7 is a sectional detail showing the holding unit installed in a sash;

Figure 8 is a detail in perspective of the lower sash used in this embodiment;

25 Figure 9 is a detail in perspective of the upper sash used in this embodiment;

Figure 10 is a front end elevation of the holding unit;

30 Figure 11 is a rear end elevation of the holding unit;

Figure 12 is a plan of an assembled holding unit with the roller in extended position;

35 Figure 13 is a similar view to that shown in Figure 12, with the roller retracted;

Figure 14 is a detail of the cylindrical body with the stem used in this embodiment;

Figure 15 is a detail of the propelling spring used to propel the roller mechanism;

40 Figure 16 is a detail of the roller;

Figure 17 is a sectional detail taken longitudinally through the shell used in this embodiment; and

45 Figure 18 is a sectional detail of the detachment taken longitudinally through it.

Similar reference characters refer to the same parts throughout the drawings.

In the drawings, a conventional form of window frame 10 of rectangular contour is indicated.

50 It is boxed in at the vertical sides 60 to fit into the building construction for which it is adapted.

The inner walls 11 of the vertical sides are constructed to receive the two sliding upper and lower sashes 12 and 13 used in it. The left hand

55 inner faces of the walls 11 are formed to provide

a parting strip 14 in the middle, at the sides of which are angular channel surfaces 15 which rake towards the strip. Each of these channels 15 is surmounted by a thin flat strip 16 of metal or other suitable material and fastened in place by screws 17. Longitudinal recesses 18 are provided at the sides of the channels 15, and serve to act as tracks for the peripheral longitudinal lips 19 at the edge of the sash stiles 20. They are formed arcuately at 21 to cooperate with the arcuate portions 22 of the exterior surface of the channels 15 of the frame, when the sashes are allowed to settle themselves in the frame. This takes place under the action of the wedging propensity of the sash surfaces against the strips 16.

The sash stiles have a sectional contour as indicated in Fig. 2. The lips 19 fit into the tracks 18 and the arcuate surfaces 21 and 22 coordinate with each other, with the inwardly extending angular surfaces 23 running on the strips 16. A molding strip 24 is attached to the upper horizontal rail 25 and is cut out at 61 to serve as a guide running on the strip 14. This keeps the sash aligned properly in the frame. It also extends out to seal up the space between the front and rear sashes 12 and 13 when the window is closed, and the upper rail 25 is in alignment with the lower rail 26. When this happens the lower bar 26 of the upper window 12 brings a ledge 27 on it against the molding strip 24 underneath.

The right hand stiles 20 of the lower sash 13 and the right hand stiles 30 of the upper sash 12 have their inner surfaces 28 and 29 respectively contoured to receive the window panes 33 and 32 respectively and give same an attractive appearance. They are held in place in any conventional or suitable manner.

The left hand or opposite wall interior surfaces of the vertical sides of the window frame are flat but inwardly angular with a rail 16 imbedded and fastened to them. On this rail travels a roller 35 having a tapered exterior adapted to angularly conform with the rail 16. This roller 35 has an axle fixed in a bearing 36 mounted on a cylindrical body 37 reciprocable in the well 38 of a cylindrical shell 39 and pressed forward or outwardly resiliently by a coiled propelling spring 40. An open or cup-like chamber 41 is provided in the body 37 in a position opposite to that of the roller, and a stem 42 integral with the body 37 extends through and beyond it. The stem 42 is arranged to align with the interior of a sleeve 43 extended inwardly into the well 38 and is movable in it. The bottom 44 of the well supports the sleeve rigidly. The stem 42 is long enough to extend just beyond the outer face 45 of the bottom 44 so that a movable lug 48 is pivoted with a small spring 49 forcing it outwardly. The spring 49 is imbedded in the stem 42, and acts in a direction at right angles to the axis of the cylindrical parts. A pair of slots 50 disposed oppositely to one another in the wall of the shell serve as guideways for a transversely projecting rod 51 to travel up and down it. The rod 51 is installed transversely in a passage 52 through the cylinder 37 and is arranged to keep the latter positioned properly aligned with the roller, so the latter will travel on the rail 16.

The components 35, 36, 37, 38, 40 to 52 inclusive are parts of a holding unit 63. A flange plate 53 is mounted on the roller end of the unit and has holes 54 through which screws 55 pass to

hold it to the sash stile and generally flush with the surface thereof. When the roller 35 is pushed back into the shell 39 it is out of the way. The side of the stile is drilled to receive a locking detent 56. This locking detent consists of a screwed-in sleeve 59 attached to the wall of the shell 39 with a plunger 57 operable exteriorly for engaging the head of the stem 42. This plunger is used for loosening the lug 48 from contact with surface 45 of the shell 39 when the roller is restrained in the shell and flush with the face of the stile. A coil spring 58 holds the plunger inside the sleeve 59 until the user pushes the plunger against the spring.

In the operation of the invention, the removable sashes are inserted sideways in one side of the window frame with the roller 35 retracted in the shell 39 and held in this position due to the engagement of the detent plunger 57 with the lug 48 and then directing the sashes in a tilting manner against the left hand side of the sash, into the left hand side of the frame, as shown in Figure 5. Then the right hand side of the sash is pushed back into place. This flattens the sash up against the strip 14. Then the detent 56 is operated by pushing against the spring 58 so the plunger 57 releases the lug 48 and allows roller 35 to be forced outwardly by the spring 40 to frictionally engage the sash. The rollers permit sliding movement of the sashes during opening and closing thereof. The tapered rollers 35 of all the holding units used travel on the angular rails and tend to wedge the sashes against the strips and provide tightness. This is by reason of the angular positions of the rails and that of the tapered faces of the rollers. This eliminates drafts and rattling. At the same time, this construction affords sufficient friction to enable the sashes to be held in any position they may be lifted to. This overcomes the need for sash weights to balance the sashes.

Any movement of the sashes up and down in the frame tends to press them towards the middle of the frame and against each other. The removal of the sashes is accomplished by a process opposite to their insertion and placement in the frame.

It will be noted that the formation of the stem 42 is that of a cylindrical shaft with its swinging head 48 overhanging to catch readily on the bottom surface 45 of the body 39 and does so automatically. The plunger 57 makes contacts with a wearing pad 62 provided on the head member when the operator pushes on it. This releases the head off the surface. The opposite end portion 65 of the stem 42 is reduced in diameter to make it fit more effectively in the hole 66 arranged in the partition 64 for it. The normal position of the roller in the holding unit is within the shell, out of the way. When released to project from the shell, the roller under the action of the propelling spring 40 presses outwardly and makes contact with the rail in the window frame. The stem 42 passes through the sleeve 43, which serves as a positive guide and controls the inward movement of the body, as well as a post for retaining the spring 40 from bending or getting out of alignment. The rod 51 passing through the body 37 into the slot 50 prevents the body with its roller 35 from twisting out of line with the rail and latter runs on. Otherwise the roller would not be held in proper alignment and unnecessary or undesirable alignment between these two would result. The flat bar 67 extending out from the rail of the lower sash 13 serves as a handle for manipulating the

sash both during raising and lowering, as well as removal and insertion in the window frame. A resilient stop clip 68 is used for locking the lower sash 13 in its raised position.

While but one form of the invention is indicated in this application and shown in the drawings, it is not desired to limit it to this particular form as it is appreciated that other structures and construction could be made that would employ the same principles and come within the scope of the appended claims.

Having thus described the invention, what is claimed is:

1. In combination with a window frame having opposite vertical walls, a parting strip located medially of the walls to form channel surfaces slanting inwardly towards the opposite vertical faces of the strip, a pair of window sashes cooperating with the window frame, aligned conical rollers carried by an outer edge of said sashes, 20 said rollers being slideable along the aforesaid channel surfaces and means for forcing said rollers against said channel surfaces whereby the sashes constantly tend towards each other to insure tightness therebetween.

2. The combination set forth in claim 1, wherein the rollers are received in housings provided in the sashes and means for locking the rollers within the housings and out of contact with the aforesaid channel surfaces, to allow removal of 30 the sashes from the window frame.

3. Locking means between a window sash and a window frame comprising a housing in the sash along one edge thereof, means for securing the housing to the sash, a cylindrical body slideable within the housing, bearings carried by said

body at one end thereof, a roller mounted in said bearings, said roller sliding with said body towards and away from the window frame, a spring in the housing biasing the body and roller outwardly of the housing, a guiding sleeve in the housing at the end thereof opposite to the roller, a stem integral with the cylindrical body and slidably mounted in the guiding sleeve and protruding outwardly thereof, a lug pivoted at the free end of the stem, a spring carried by the stem and biasing the lug outwardly and detent means for engaging and releasing said lug.

4. Locking means as set forth in claim 3, including a pin and slot connection between the housing and the cylindrical body to maintain the roller in proper alignment.

JOSEPH E. HAYNES.
